UNITED STATES PATENT OFFICE.

NICHOLAS S. VEDDER AND FRANCIS RITCHIE, OF TROY, AND TOBIAS S. HEISTER, OF LANSINGBURG, ASSIGNEES TO NICHOLAS S. VEDDER, OF TROY, NEW YORK.

DESIGN FOR A DWARF STOVE.

Specification forming part of Design No. 6,314, dated December 17, 1872.

To all whom it may concern:

Be it known that we, NICHOLAS S. VEDDER and FRANCIS RITCHIE, each of the city of Troy, in the county of Rensselaer and State of New York, and TOBIAS S. HEISTER, of Lansingburg, in the said county and State, have jointly invented and produced a new and original Design for Dwarf Stoves, of which the following is a specification, reference being had to the accompanying wood cut or engraving of a stove having our said design.

One part of our invention consists of the compound ornament or ornaments A, shaped and arranged on a door or doors or panel or panels of a stove or range as represented in the aforesaid engraving. Another part consists of the combination of the ornament or ornaments A and border molding or moldings B as shown in the aforesaid cut. Another part consists of the compound ornament or ornaments C, shaped and arranged on a door or doors or panel or panels of a stove or range as represented in the engraving. Another part consists in the combination of the panel ornament or ornaments C and ornamented border molding or moldings D, as shown in the cut. Another part consists of the design for the lower front plate E, as distinguished by the

ornamented arch-molding f and corner ornaments g, shaped and arranged together as shown in the wood-cut. Another part consists of the design for the upper front plate H, as distinguished by the panel i, shaped and ornamented in the particular manner shown in the cut.

What we claim as our invention is—

1. The ornament or ornaments A, shaped and arranged as herein specified.
2. The combination of the ornament or ornaments A and ornamented molding or moldings B, as herein described.
3. The ornament or ornaments C, shaped and arranged as herein set forth.
4. The combination of the ornament or ornaments C and ornamented molding or moldings D, as described.
5. The design for the lower front plate E, as described.
6. The design for the upper front plate H, as set forth.
